THREAD-CONTROLLER FOR SEWING MACHINES

Andrew B. Clayton, Union, N. J., assignor to The Singer Manufacturing Company, Elizabeth, N. J., a corporation of New Jersey

Application June 23, 1934, Serial No. 732,041

2 Claims. (Cl. 112—248)

This invention relates to sewing machine thread-controllers more particularly of the rotary type commonly used to control the looper-thread of a chain-stitch sewing machine.

5 The invention has for an object to provide a rotary thread-controller of simplified and improved construction, which has an easy action on the looper-thread and which will not catch and wind looper-thread from the source of supply, in case of thread-breakage. Another object 10 of the invention is to provide a rotary thread-controller which may be quickly and easily threaded up, or re-threaded with a minimum loss of time in case of thread-breakage. A further 15 object of the invention is to provide a thread-controller which adequately guards the looper-thread from becoming fouled by abnormal contact with adjacent moving parts or by oil from adjacent working bearings.

20 With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a top 30 plan view of the cloth-plate and bed of a multiple-needle double-thread chain-stitch sewing machine embodying the invention. Fig. 2 is a vertical section on the line 2—2, Fig. 1. Fig. 3 is a vertical section at right angles to the line 2—2, Fig. 1. 35 Fig. 4 is a fragmentary elevational view of a lead-in thread-guide looking in the direction of the arrows 4—4, Fig. 1. Fig. 5 is a bottom plan view of the thread-controller guard-plate and associated thread-guides. Fig. 6 is a perspective view 40 of the upper side of the guard-plate and associated thread-guides, and Fig. 7 is an enlarged sectional view on the line 7—7, Fig. 1.

The invention is disclosed as embodied in a double-thread chain-stitch sewing machine of a 45 type represented in United States Patents Nos. 1,100,124, of June 16, 1914, and 1,569,912, of Jan. 19, 1926. Such a machine has the usual bed 1 and bracket-arm standard 2. The bed 1 carries the usual raised cloth-plate 3 over which the 50 work passes.

The stitch-forming mechanism comprises the usual reciprocating needles 4 and complementary thread-carrying loopers 5 which latter are actuated in the usual manner, as shown in said 55 patents, by the inclined crank 6 on the rotary main-

shaft 7 journaled above the bed 1 and below the cloth-plate 3 in suitable bearings including the bearing 8 in the bearing pedestal 9.

The cloth-plate 3 carries the usual throat-plate 10 having the needle-holes 11 and clearance slots 12 for the feed-dog 13 which cooperates with the presser-foot 14 to feed the work and is carried by the usual feed-bars 13^x. The main-shaft 7 carries the usual feed-eccentric 13' and feed-lift eccentric 13''.

To control the looper thread or threads, there is mounted on the shaft 7, close to the bearing 8, a rotary thread-cam 15 having on that face thereof adjacent the bearing 8 an oil-sling 16. It will be observed that the thread-cam 15 is a 15 single-disk cam, that is, it has no peripheral groove therein such as has heretofore been commonly provided to receive the usual slotted cast-off and which groove has been a source of annoyance due to its tendency to wind looper-thread from the supply in case of thread-breakage.

20 Mounted on the bearing pedestal 9 is a bracket 17 to which is screwed the guard-plate 18 having a slot 19 therein through which the thread-cam 15 projects. The guard-plate 18 is thus mounted above and parallel to the shaft 7 and below the cloth-plate 3 which has an opening 3' therein exposing the guard-plate; such opening being normally closed by the removable cover-plate 3''. The guard-plate 18 also covers the feed-eccentric 13' and prevents the looper-thread from being fouled thereby.

25 Adjustably secured by screws 20 on top of the guard-plate 18 at opposite sides of the plane of the thread-cam 15 are the thread-guides 21 each of which is in the form of a hook having a forwardly opening thread-receiving throat 22, Fig. 6, leading to the bottom or reverse bend 23 which 30 guides the looper-thread.

35 Spaced above and parallel to the guard-plate 18 is the thread-detainer 24 in the form of a U-shaped wire loop embracing the thread-cam 15 and secured by its legs to the plate 18 by the clamp-screw 25 and double-grooved clamping washer 26, Fig. 7; the thread-detainer being held 40 spaced above the guard-plate by the supporting spacing washer 27. The free end 24' of the thread-detainer is inclined upwardly adjacent the open throats 22 of the thread-guides 21 to facilitate the lateral introduction of the looper-thread simultaneously to the thread-guides 21 and under the thread-detainer 24, in threading up the 45 machine. The legs of the thread-detainer 24 are substantially parallel to the cam 15. The guard- 50

plate 18 and thread-detainer 24 constitute thread-detaining means the spaced surfaces of which define a horizontal thread-passageway which extends in opposite directions entirely beyond the periphery of the cam 15. Hence the cam 15 may be turned in either direction without dislodging the thread from such passageway.

Also mounted on the guard-plate 18 at opposite sides of the plane of the thread-cam 15 are 10 the similar angle-plates 28 having therein the vertical thread-guiding slots 29 and thread-retaining spring wires 30 permitting lateral introduction of the looper-threads, or in other words providing a "self-threading" construction.

15 There is preferably secured to the under side of the guard-plate 18 a thin fibre strip 31 the edge 32 of which preferably contacts or wipes against the side of the thread-cam 15 nearer the source of thread-supply and prevents the looper-thread from being carried to and wound upon the thread-cam hub 15' in case of thread-breakage.

There is also secured to the under side of the guard-plate 18 an inverted U-shaped oil-guard 25 33 having an inwardly extending flange 34 which overhangs the oil-sling 16, as shown in Fig. 3.

The cloth-plate 3 is provided with a thread-slot 35 extending from the opening 3' toward the rearward side of the standard 2 where the 30 thread-tension devices (not shown) are commonly located. The thread-slot 35 is bridged under by an integrally cast loop 37, Fig. 4, which serves as a cross-brace as well as a lead-in thread-guide. A guard-flange 38 screwed to the bed 1 35 is formed with a large threading hole 39 connected by a slot 40 to the slot 35.

To thread the loopers, the ends of the looper-threads from the tension-devices are first inserted through the large hole 39 in the guard-plate and then drawn forwardly above the cloth-plate 3 to a point beyond the thread-controller cam 15. The threads are then passed laterally 40 of themselves and downwardly through the slot 35 and under the retaining wire 30 into the respective guide-slots 29 in the guide-plates 28. The threads are then grasped between the guide-plates 28 and pulled toward the operator and passed under the free ends of the guides 21 and 45 detainer 24. The loopers 5 are then threaded in 50 the usual manner. When the machine is started,

the thread between the guides 28 is carried by the cam 15 to the bottoms 23 of the throats 22 in the guides 21 and under the detainer 24. The cam 15 is shaped to take-up the pay-out looper-thread as required by the loopers and prevent the formation of undue slack in the looper-thread at any point in the stitch-forming cycle. The thread-loop engaged by the cam 15 is confined to a substantially horizontal movement by the guard-plate 18 and overlying detainer 24. The 10 guard-plate 18 may act as a stripper to prevent the cam 15 from carrying the engaged thread-loop around the shaft 1.

The bearing 8, as well as various other bearings of the machine, is lubricated by an oil-pipe 15 41 leading from an oil-main 42 to the horizontal oil-duct 43 extending under the bushing 8 and in communication with the oil-hole 44 leading upwardly through the bushing 8 to the bearing surfaces. 20

The invention is not to be understood as limited to the details of construction and relative arrangements of parts shown and described in this detailed disclosure of a preferred embodiment of the invention. It is obvious that various 25 modifications may be made by one skilled in the art within the spirit and scope of the invention.

Having thus set forth the nature of the invention, what I claim herein is:—

1. A sewing machine having a bed, a standard 30 and a cloth-plate raised above said bed and formed with an opening therein and a thread-slot extending from said opening to the edge of said cloth-plate adjacent said standard, a thread-guide carried by said cloth-plate and bridging 35 under said slot adjacent said standard, a rotary shaft journaled below said cloth-plate, a looper actuated by said shaft, a rotary looper-thread controller cam mounted on said shaft below the opening in said cloth-plate, thread-guides co-operating with said thread-controller cam, and a removable cover for said opening. 40

2. In a sewing machine, a bed having a bearing pedestal, a rotary shaft having a bearing in said pedestal, a rotary thread-controller cam mounted on said shaft and formed with a hub having an oil-sling adjacent one end of said bearing, and an inverted U-shaped oil-guard 45 embracing said oil-sling.

ANDREW B. CLAYTON. 50
